Americus V. Cook

UNITED STATES PATENT OFFICE.

AMERICUS VESPUCIUS COOK, OF DEXTER, MISSOURI.

CHURN.

SPECIFICATION forming part of Letters Patent No. 363,450, dated May 24, 1887.

Application filed March 12, 1887. Serial No. 230,694. (No model.)

To all whom it may concern:

Be it known that I, AMERICUS VESPUCIUS COOK, a citizen of the United States, residing at Dexter, in the county of Stoddard and State 5 of Missouri, have invented a new and useful Improvement in Churns, of which the following is a specification.

My invention relates to improvements in churns, the objects being to lessen the labor of 10 churning and cleaning the churn, to lengthen or shorten the stroke of the dasher-rod when desirable, and to provide a churn of simple and durable construction. These objects I attain by means of the construction and novel 15 arrangement of parts hereinafter described, embraced in the appended claims, and illustrated in the accompanying drawings, in which—

Figure 1 represents a perspective view of 20 the improved churn, seen from the side on which the churn barrel or cylinder is placed. Fig. 2 is a side elevation of the same. Fig. 3 is a detail sectional view showing the connection of the pitman, cross-head, dasher-rod, and 25 nut. Fig. 4 is a perspective view of the long connecting-bolt detached. Fig. 5 is a sectional view showing the cross-head.

Referring to the accompanying drawings by letter, A designates the base-plate of the main 30 frame, and B is the upper plate of the same.

b b are uprights, which connect the side edges of the base-plate near one end with the lower surface of the upper plate, B, near its side edges.

C is a vertical bar, which stands from the 35 end of the base-plate adjacent to the uprights b b, is secured to the edge of the upper plate, B, and extends above said plate to a suitable height, as shown in the drawings; and C' is a bar rising from the upper plate parallel to and a 40 suitable distance inward from the bar C, and extending to the same height as the latter. c is a stay or brace rod connecting the upright bar C' with the plate B.

D is a large gear-wheel secured on a horizontal shaft, d, journaled in bearings fixed upon corresponding sides of the bars or uprights C C'. The said gear-wheel meshes with a pinion, E, on a shaft, e, journaled in bearings on 45 the same edges of the said bars or uprights above the wheel D. The wheel and pinion are situated between the uprights, and the shaft

d is extended outward from its exterior bearing and squared to engage a crank-handle, d', which gives motion when rotated to the mechanism. Secured to the inwardly-extended end 55 of shaft e is the disk F, provided with a radial series of adjusting-openings, f f.

G is a pitman, the upper enlarged end of which may be attached to the disk by a screw 60 or pin, g, passing through an opening in said end, and engaging in any one of the openings f. The lower end, g', of the pitman is also enlarged and provided with an opening, through which it is connected to the cross head H by a 55 long bolt, h.

The cross-head H is rectangular in shape, and provided in its ends with the notches h h', which fit and slide upon the inner corresponding edges of the vertical bars i i of the guide-frame I, standing from the upper plate, B, a 70 suitable distance in front of the bar C'.

K is the dasher, of any suitable size, shape, and construction; and k is the dasher-rod rising centrally therefrom, and provided with these 75 series of adjusting-openings k'. The bolt h, after passing through a central transverse opening in the cross-head, passes through any desired one of the openings k', the stem of the bolt being reduced in size and having its 80 threads removed at k², where it rests in said opening, and for a short distance on each side of the dasher-rod.

L is an elongated nut having its inner or binding surface, l, made convex, so as to enter 85 and, when necessary, bind upon the corresponding vertical concave portion, l', of the dasher-rod.

On account of the adjusting-openings k' being extended laterally and the stem of the screw being reduced where it passes through one of said openings, the nut L, when not screwed up against the dasher-rod, will, while preventing said rod from being displaced, allow it and the attached dasher to swing freely 90 in all directions within the churn barrel or cylinder M, placed below on the base-plate A, which free motion stirs the cream up in all directions and brings the butter quicker and with less labor. By turning the nut L tightly against 95 the dasher-rod, its convex part will bind in the convex part l' and hold the dasher-rod rigid. When so held, it will be guided vertically by the curved notch l' on the edge of the plate B.

The lateral adjusting openings k' of the dasher-rod are of such a diameter that the threaded portion of the bolt h will pass readily therethrough, and consequently when the rod is hung on the reduced portion of said bolt it will have a free play thereon. If, however, the nut L be turned up so as to bind against the dasher-rod, it will force the said rod into the notch t' , and the rod will then have only a vertical reciprocating motion.

By means of the adjusting openings k' the dasher-rod can be extended from the cross-head downward to suit churn-barrels of different heights, and by means of the openings f and screw or pin g the stroke of the pitman can be changed.

In operation, the motion of the handle d' is communicated to the disk F through the wheel D and pinion E . The rotation of the disk F reciprocates the pitman G , and simultaneously operates the cross-head H and the dasher-rod, as will be readily understood.

Having described my invention, I claim—

1. In a churn, the combination of the dasher, the dasher-rod provided with a longitudinal series of lateral adjusting-openings, the pitman, the cross-head reciprocating in a guide-frame attached to the main frame, and the bolt connecting the lower end of the pitman, the cross-head, and the dasher-rod together, reduced in diameter, and having no threads at

and on each side of the portion resting in one of the adjusting-openings in the dasher-rod, and engaging a suitable nut to retain the latter in place, substantially as described.

35

2. In a churn, the combination of the dasher, the dasher-rod k , provided with the lateral openings k' and the vertical concave portions t' , and the plate B , having the guide-notch t on its edge, of the nut L , having the convex binding-surface l , the screw-bolt h , having the reduced and unthreaded part h' , the cross-head, the pitman G , and mechanism, substantially as described, whereby said pitman is actuated, substantially as specified.

45

3. In a churn, the combination of the dasher, dasher rod having lateral adjusting-openings, the bolt having a reduced unthreaded part to enter one of said openings, and the reciprocating cross-head, with the pitman, the disk F , provided with the adjusting-openings f , to any one of which the upper end of the pitman may be engaged by a screw or pin, g , and means, substantially as described, whereby said disk is rotated, substantially as specified.

55

In testimony that I claim the foregoing as my own I have hereto affixed my signature in presence of two witnesses.

AMERICUS VESPUCIUS COOK.
